UNITED STATES PATENT OFFICE.

THOMAS HENRY JONES, OF NOTTINGHAM, ENGLAND.

KNITTING MACHINE.

Application filed January 27, 1925. Serial No. 5,070.

To all whom it may concern:

Be it known that I, THOMAS HENRY JONES, British subject, residing at Breck Hill Road, Woodthorpe, Nottingham, England, have 5 invented new and useful Improvements in or Relating to Knitting Machines, of which the following is a specification.

This invention comprises improvements in or relating to knitting machines, and 10 has more particular reference to the production of double thread fabrics composed of plating and ground threads, the object of the invention being to enable a great range or variation of patterns and effects to be 15 produced in such fabrics by simple and improved means for feeding the threads to the needles, the invention being applicable to circular, flat bar or warp machines.

According to my invention means are in- 20 corporated for so operating and controlling the movement of the thread guides so as to enable numerous and varied patterns and effects to be produced at will, such for instance, as vertical, horizontal or diagonal 25 stripes, squares or diamonds; said operation and control of the guides being in the case of circular knitting machines effected by means of suitably shaped or designed pattern rings.

For the purpose of more fully describing the nature of my said invention, reference will now be made to the accompanying drawings; wherein:—

Fig. 1 is a part sectional elevation illustrating the present invention applied to a 35 circular knitting machine.

Fig. 2 is a side elevational view of Figure 1 looking in the direction of arrow X.

Fig. 3 illustrates in side elevation and 40 Figure 4 in end elevation suitable mechanism for transmitting movement to a cam member shown in Figure 2 for retaining the thread guides in a fixed position, and releasing said guides at predetermined intervals.

Fig. 5 is a part sectional detail view showing modified means for controlling the movement of a cam or pattern ring which transmits movement to the thread guides.

One convenient method of carrying out 50 the invention will now be described as applied to a circular knitting machine of the latch needle type.

Fixed to a suitable stationary part of the machine on the exterior of and adjacent to 55 the rotating needle cylinder 1 is a bracket

or block 2 having a vertical bore or passage therethrough which slidably accommodates a plunger or spindle 3. This spindle extends down below the bracket 2 to a suitable extent and has a lateral projecting arm 4 secured near its lower end between which and the underside of the guide bracket 2 is provided a coiled spring 5, which spring 5 surrounds the spindle 3 and tends to pull same downwards. The upper end of the 60 spindle 3 projects beyond the bracket 2 and is pivotally connected to two lever members 6, 7 constituting the guides or carriers for the plating and ground threads, said levers extending in a radial or approximately radial manner towards the needle cylinder 1.

The one lever 6 of the two levers, hereinafter called thread guides, is pivoted to a stationary pivot 8^a at a position intermediate 75 the sliding spindle 3 and the needles 1, the second thread guide 7, being pivoted to a fixed pivot 7^a at a position on the opposite side of said spindle 3, the arrangement being such that a vertical movement of the 80 sliding spindle in either direction effects a raising of the one thread guide and a corresponding lowering movement of the other guide, so as to bring either the plating 85 thread or the ground thread into the lowermost position when fed to the needles, and consequently also bring either of said threads into prominence at the front of the fabric.

It will therefore be appreciated that the 90 vertical displacement of the spindle 3 operating the thread guides 6, 7 at predetermined intervals will produce patterns or designs in the fabric. Preferably, one or 95 more rotatable pattern or cam rings is or are furnished, said ring or rings (two of which are shown at 8 and 9 in Figure 1) having cam faces 10 or cam bits which during rotation are caused to engage the lower end 100 of the vertically displaceable spindle 3 and press same upwardly against its spring 5, such spring causing the spindle to follow the contour of the pattern or cam ring on which it bears. When the spindle 3 is required to be operated by both rings 8, 9 the 105 lower end of said spindle is enlarged to engage with both rings. The cam rings 8, 9 are designed to be independently moved through mechanism, 80, 90, not illustrated in detail.

If only one pattern ring is required to act on the spindle 3, the spindle is formed so as to engage only with the pattern ring which is to operate it.

5 The nature of the cams on the pattern ring determines the interval between the movement of the thread guides 6, 7 and consequently also the width of the stripe produced in the fabric.

10 Any suitable number of pairs of thread guides as above may be incorporated on the machine, said number being only limited by the number of thread feeds.

15 By varying the shape of the pattern cam rings and the speed of travel thereof relative to the needles, the pattern produced may be varied in many ways. For example, in a machine having a stationary cam box and revolving cylinder where a plurality of pairs of thread guides are utilized and the pattern ring is timed to travel at the same speed as the needles, a number of parallel vertical stripes will be produced. If, however, the pattern ring is geared to travel 25 slightly faster or slower than the needles, then diagonal stripes will result. If again two pattern rings are provided each travelling in the same direction at a different speed, one faster and the other slower than the needles, one of said rings being caused to operate alternate pairs of thread guides, then a diamond or crossed pattern will result.

30 It will thus be seen that by the employment of different colours, qualities or kinds of threads, numerous patterns and effects can be obtained.

35 Further, if the sliding spindle operating the thread guides be moved to a position in which the pair of guides are on a level, i. e., in the same horizontal plane, the two threads will be so fed to the needles that a random or uncertain pattern will result.

40 In some cases also, it is desirable to fix 45 or lock the thread guides so that one of the threads is continually laid in the front and the other at the back of the fabric for a predetermined number of revolutions of the needle cylinder, so as to provide a uni-coloured band extending completely round the fabric at intervals, and in one method of accomplishing this an annular ring 11 50 may be slidably assembled upon the machine bed or other part, said ring having a raised cam piece 12 fixed thereto (Figure 2). Screwed into an outwardly projecting lip 13 on ring 11 is the one end of a rod 14 which extends tangentially relative to said ring, and is pivotally connected at its other end within a slot 15 in a lever 16 pivoted between its ends at 17 to fixed bracket 18. Operating upon the cam truck or roller 19 at the lower end of lever 16 is a suitably shaped cam wheel 20 which at predetermined intervals rocks lever 16 on its pivot

17 against the pull of spring 21 and shogs the rod 14 to push the cam 12 beneath the small arm 4 on spindle 3 and raise said spindle to a degree sufficient to clear same of the rotating pattern rings 9, 10; thus retaining 70 the guides from movement.

75 Any suitable or known mechanism may be incorporated for rotating the cam 20 at the requisite speed for locking or fixing the guides 6, 7 at the required times. For example, as shown in Figures 3 and 4, a cam 22 on shaft 23 may be caused to operate on a lever 24 pivoted at 25 to rock same against the resistance of a spring 26, said lever 24 carrying a clawer 27 continually engaging with a ratchet wheel 28, which ratchet in rotation traverses a chain or band 29 having ratchet shaped high links or members 30 at intervals thereon. These links engage with and turn a further ratchet wheel 31, with 80 which the cam wheel 20 rotates in unison, a further ratchet 32 being also preferably mounted to rotate with the wheels 31 and 20 and having a spring pressed pawl 33 engaging therewith to prevent backward movement of said wheels. A spring pressed pawl 34 may also be provided for retaining the ratchet 28 from backward rotation.

85 In the modification shown in Figure 5 which is adaptable for use in a machine having a revolving cam box a single pattern or cam ring 9^b is traversed to and fro in a circular path to a short distance instead of being rotated completely round as in the foregoing arrangement. To accomplish this, a gear wheel 35 rotating with the cam box meshes with a bevel 36 on the worm shaft 37, the rotation of said worm shaft turning the worm wheel 38 and through the crank arm 39 and connecting link 40 transmitting a to and fro motion to the ring 9^b so as to move the cam portion thereon into and out of engagement with the spindle 3.

90 The invention can be utilized in connection with machines producing either tucked or plain knitted fabrics or a combination of both, and in the last named case the tucking may be effected either from the same patterning rings before described for operating the thread guides, or from an additional patterning ring.

95 Further in the production of fabrics according to this invention no loose, floating or additional threads are required, the produced fabric being of even thickness throughout.

I claim:

1. In a knitting machine, the combination with a rotatable cylinder carrying the needles, of guides for delivering thread to the needles, arranged to move so as to occupy alternately different positions, whereby thread from any guide may be transferred from the back to the front of the fabric, or vice versa, accordingly as the 100

guide is operated, stationary supports for the thread guides, a pattern cam ring arranged concentrically with the needle cylinder and operating to directly move the 5 thread guides so as to deliver their threads to the needles to produce determined designs in the fabric being knitted, the cam ring being capable of variable rotary movements with reference to the movements of the 10 needle cylinder, whereby the thread guides will function in differently timed relations to the knitting operations to cause different effects in the completed article to be produced, accordingly as the cam ring is operated.

2. The combination stated in claim 1, in which are employed a pair of concentric

cam rings, and means for independently moving the rings.

3. The combination stated in claim 1, including also a concentric ring carrying a cam piece arranged to move the thread guides into such position that they will not be acted on by the pattern cam, and whereby so long as the said cam piece is 25 in operation thread from one of the guides is laid in the front of the fabric, and from the other at the back thereof, producing a circular band in the design being knitted, and means whereby the said concentric ring 30 is operated to move the cam piece into operation as may be desired.

THOMAS HENRY JONES.
